By my authority

UNITED STATES PATENT OFFICE.

RUDOLPH W. RIESS, OF PHILADELPHIA, PENNSYLVANIA.

ATTACHMENT FOR BICYCLES.

SPECIFICATION forming part of Letters Patent No. 469,722, dated March 1, 1892.

Application filed October 12, 1891. Serial No. 408,526. (No model.)

To all whom it may concern.

Be it known that I, RUDOLPH WILLIAM RIESS, of the city and county of Philadelphia, and State of Pennsylvania, have invented an Improvement in Attachments for Bicycles, of which the following is a specification.

My invention relates to attachments for bicycles; and it consists of certain improvements which are fully set forth in the following specification and are shown in the accompanying drawings, which form a part thereof.

More particularly my invention relates to devices for connecting two bicycles together, so that they may move in unison as one machine; and the particular improvement of the present invention relates to the construction of the connecting rod or rods to allow one machine to move slightly independently of the other in going over irregularities in the road, turning curves, &c., thereby relieving the machines of strains. In turning curves one of the two connected bicycles tends to move slightly in advance of the other, and in riding over ruts or inequalities in the road the machines tend to change their relative positions slightly to compensate for the inequality of the road. With a rigid connection between the two machines there will be more or less of a strain upon the machines under these circumstances; and it is the object of my invention to entirely overcome this objection.

In carrying out my invention I form the connecting rod or frame by which the machines are joined together in parts and unite the parts by a spring, so that each part may move slightly with reference to the other part when either machine tends to move independently of the other. The instant this strain is, however, removed the spring draws the parts of the connecting-rod back into their normal relative positions.

In the drawings, Figure 1 is a plan view of a pair of bicycles united by my improved connecting-rods. Fig. 2 is a similar view in which the construction of the connecting-rods is modified. Fig. 3 is a sectional side elevation of a part of the connection with the ends in section and showing in dotted lines the movements of the rods in a vertical plane. Fig. 4 is a plan view of the same, illustrating in dotted lines the movements in an horizontal plane; and Fig. 5 is a perspective view of the spring for uniting the parts of the connecting-rod.

A and A' are two machines which are to be connected together.

B is the connecting-rod by which the frames of the machines are united by means of end-clamping pieces b on the ends of rod, adapted for connection with the machine. The clamping-pieces may be adapted for detachable connection with the machines. This connecting-rod is made in parts, having its parts united by a spring C.

It is not material to my invention, when broadly considered, in which manner the parts of the connecting-rod B are united by the spring nor what is the particular character of the spring. I prefer, however, to employ a coiled spring C, having its ends c inserted in holes a in the ends of the rods and clamped therein by set-screws D.

If desired, a second connecting-rod E may be employed to connect the rear portions of the machine, and the wheel-forks F may be similarly connected.

The connecting-rods may be provided with brace-pieces G adjacent to their ends, adapted for attachment to different parts of the machine, as shown in Fig. 1, or these braces may be omitted, as shown in Fig. 2. These and other minor details of construction may be varied without departing from the invention.

What I claim as new, and desire to secure by Letters Patent, is—

1. A connecting-rod for connecting two bicycles together, consisting of a rod having its end adapted for attachment with the frames of the machines and formed in parts and having said parts connected by a spring.

2. A sectional connecting-rod for uniting two bicycles together, having its sections united by a spring connection.

3. A connecting-rod for connecting two bicycles together, consisting of a rod having its end adapted for attachment with the frames of the machines and formed in parts and having said parts connected by a coiled spring, with its ends let into holes in the ends of the parts.

In testimony of which invention I have hereunto set my hand.

RUDOLPH W. RIESS.
